UNITED STATES PATENT OFFICE.

HUNTER H. DOVELL, OF URBANA, OHIO, ASSIGNOR OF ONE-HALF TO
GEORGE A. LAMBERT AND JOHN W. LAMBERT, OF ANDERSON,
INDIANA.

CAR-DOOR HASP.

SPECIFICATION forming part of Letters Patent No. 780,412, dated January 17, 1905.

Application filed July 13, 1904. Serial No. 216,388.

To all whom it may concern:

Be it known that I, HUNTER H. DOVELL, a citizen of the United States of America, and a resident of Urbana, county of Champaign, State of Ohio, have invented certain new and useful Improvements in Car-Door Hasps, of which the following is a full and clear specification, reference being had to the accompanying drawings, in which—

10 Figure 1 is a side elevation of a portion of a car, showing the manner of using this device to fasten the door entirely closed; Fig. 2, a similar view showing its manner of use in locking the door slightly open for ventilation; 15 Fig. 3, a perspective view of the device detached, and Figs. 4, 5, and 6 views of various details fully hereinafter described.

This invention has for its objects to provide a simple and inexpensive device especially 20 adapted for freight-car doors and which will permit the door to be securely locked entirely closed or slightly open for ventilating purposes.

To the accomplishment of these objects and 25 such others as may hereinafter appear the invention consists of the parts and combination of parts hereinafter fully described, and particularly pointed out in the appended claims, reference being had to the accompanying 30 drawings, forming a part of this specification, in which the same reference characters designate like parts throughout the several views.

Referring to the drawings by reference-letters, *a* designates the main plate of the hasp, 35 which at its inner end is provided with a hole for loose engagement with a staple *b*, fastened to the outer face of the car-door. This staple has one of its shanks fastened to the center of a plate *c*, provided with screw-holes, and its 40 other shank extended beyond said plate *c* and sharpened, so that in fastening it to the door this sharpened shank is first driven into the door until the plate *c* bears against the face of the same, and then suitable screws are inserted through the openings in the plate. This 45 staple provides a simple and secure fastening device for the hasp, and this construction I prefer; but it is obvious that any other suit-

able device may be employed for this purpose without departing from the spirit of the invention.

Near the free end of the plate *a* it is provided with two transverse slots *d*, one being located nearer the end of the plate than the other, and between the innermost slot and the fastened end the plate is provided on its front face with a headed pin *e*. At a point directly below the pin *e* the plate is provided with a horizontally-projecting eye or loop *f*.

Slidably mounted on the front face of the 60 main plate *a* is a supplemental plate *g*, which at its lower edge is provided with an outward-extending loop or eye *h*, corresponding with the loop or eye *f* and adapted to lie just above the same. This supplemental plate is attached 65 to plate *a* by the headed pin *e*, which works through a longitudinal slot formed centrally of the plate, this slot being closed at its ends, so that the supplemental plate shall be permanently attached to the main plate. Beyond 70 the slot *i* and in alinement therewith is another longitudinal slot *j*, which is approximately long enough to reach from one of the slots *d* to the other and which at its middle is widened by notches *k*, formed in its opposite edges. 75 For convenience in manipulating this slidable plate it is provided at one end with an out-turned thumb-piece *l*.

Attached permanently to the frame of the car adjacent to the door-opening and in line 80 with the staple *b* is a plate *m*, projecting from the face of which is a headed pin or lug *n*, whose head is vertically elongated so that it may pass freely through slots *d* and the widened part of slot *j*.

In fastening the door entirely closed, as in Fig. 1, the hasp is adjusted so that the head of pin *n* shall pass through the inner slot *d* and the widened part of slot *j*; the plate *g* first having been adjusted so that the notches *k* 90 shall register with said slot *d*. Then the plate *g* is slid outward until the inner end of slot *j* comes against the pin *n*, in which position the loops *f* and *h* will register. The plates may be locked in this position by passing the 95 shank of a padlock through the loops or by any

other suitable means—as, for instance, by the sliding bolt *o* shown. This bolt *o* is slidingly mounted on the projection *e* between its head and the face of the plate *g*, it being slotted vertically, so that it may have a limited vertical play and may be passed down through the loops *f* and *h* when they are brought to register and may be removed therefrom when the door is to be unfastened. The lower end 10 of the bolt, which depends below the lower loop *f*, is provided with a transverse hole, through which the seal-wire may pass to seal the door and prevent the bolt being withdrawn from the loops without breaking the seal. When this sealing-bolt is not to be used, it may be swung to one side out of the way, as is evident.

When the door is to be fastened partly open for the purpose of ventilating the car, the pin 20 *n* is passed through the outer slot *d*, the supplemental plate first having been slid outward far enough to bring its notches *k* to register with said slot. Then the plate *g* is slid inward until the outer end of slot *j* strikes 25 against the shank of pin *n*, in which position the loops *f* and *h* will register.

It will be observed that this device may be employed for other purposes than for locking car-doors; so I do not wish to be confined in 30 the use of the device. It will be apparent to those skilled in the art that various mechanical embodiments of the invention are possible, and I therefore do not wish to be limited to the exact arrangement and construction shown.

What I claim, and desire to secure by Letters Patent, is—

1. In a device of the character described, the combination of a main plate and means for fastening one end of it, said plate being provided 40 on its face with a headed pin and beyond the pin with a pair of transverse slots, one of the slots being nearer to the end of the plate than the other, said plate being also provided with an outward-extending eye or loop, a supplemental plate slidingly mounted on said main plate and provided with an outward-extending loop or eye adapted to register with the loop on the main plate and also with a longitudinal slot near its outer end which slot is widened midway its length and is adapted to 45 register with either of the transverse slots in the main plate, and a device adapted to be secured to the structure adjacent to the door and provided with a vertical elongated head adapted to pass through 50 either of said transverse slots and the widened part of the slot in the supplemental plate, for the purposes set forth.

2. In a device of the character described, the 60 combination of a main plate and means for fastening one of its ends to the door, its other end being provided with a pair of transverse slots, one being nearer the free end of the plate than the other, a headed pin or bolt adapted 65 to be fastened to the structure adjacent the

door-opening and adapted to pass through either one of said slots, and means on the plate for locking said headed pin or bolt in either of said slots, for the purposes set forth.

3. In a device of the character described, the combination of a main plate adapted at one end to be attached to the door and at its other end provided with an opening, a pin or bolt adapted to be attached to the structure adjacent the door and to pass through said opening, a sliding supplemental locking-plate on the main plate, both plates being provided with loops adapted to lie adjacent each other when the supplemental plate is in its locked position, and means for sealing or locking the two plates together consisting of a vertically-sliding bolt pivotally depending from the device and adapted to extend down through the aforesaid loops.

4. In a device of the character described, the combination of a main plate adapted at one end to be attached to the door and at its other end provided with an opening, a pin or bolt adapted to be attached to the structure adjacent the door and to pass through said opening, a sliding supplemental locking-plate on the main plate, both plates being provided with loops adapted to lie adjacent each other when the supplemental plate is in its locked position, and a vertically-movable sealing-bolt attached to the device at a point above the loops and adapted to pass down through the loops to lock the device and to be withdrawn therefrom to unlock the device.

5. In a device of the character described, the combination of a main plate and means for fastening one end of it, said plate being provided on its face with a headed pin and beyond the pin with a pair of transverse slots one of the slots being nearer to the end of the plate than the other, said plate being also provided with an outward-extending eye or loop, a supplemental plate slidingly mounted on said main plate and provided with an outward-extending loop or eye, adapted to lie adjacent to the loop on the main plate, and also with a pair of longitudinal slots, one being widened at a point in its length and adapted to register with either of the transverse slots in the main plate, a pin passing through the latter slot and into the main plate, and a device adapted to be secured to the structure adjacent to the door and provided with a vertical elongated head adapted to pass through either of said transverse slots and the widened part of the slot in the supplemental plate, for the purposes set forth.

6. In a device of the character described, the combination of a main plate and means for fastening one of its ends to the door, its other end being provided with a pair of openings, one being nearer the free end of the plate than the other, a headed pin or bolt adapted to be fastened to the structure adjacent the door-opening and adapted to pass through

either one of said openings, and means on the plate for locking said headed pin or bolt in either of said slots, said means consisting of a supplemental plate attached to the main plate and having a limited sliding movement thereon.

7. In a device of the character described, the combination of a main plate and means for attaching one end to a door, said plate being provided at its free end with an opening, a pin or bolt adapted to be secured to the frame of the structure adjacent the door-opening and to pass through the opening in the plate, a sliding supplemental locking-plate on the main plate, and means for locking these two plates together, said means consisting of a pair of loops carried one by the main plate and the other by the supplemental plate, and a device for passing through these loops and locking them against movement with respect to each other.

8. In a device of the character described, the combination of a main plate adapted at one end to be attached to the door and at its other end provided with an opening, a pin or bolt adapted to be attached to the structure adjacent the door and to pass through said opening, a sliding supplemental locking-plate on the main plate, both plates being provided

with loops adapted to lie adjacent each other when the supplemental plate is in its locked position, and a vertically-sliding locking-bolt carried by the main plate and depending through said loops, for the purpose set forth.

9. In a device of the character described, the combination of a main plate adapted at one end to be attached to the door and at its other end provided with an opening; a pin adapted to be attached to the structure adjacent the door and to pass through said opening, a supplemental locking-plate provided with a longitudinal slot, a headed pin passing through said slot and into the main plate to thereby slidably attach said supplemental plate to said main plate, both of said plates being provided with loops adapted to lie adjacent each other when the supplemental plate is in its locked position, a vertically-sliding bolt hung on the projecting headed end of said pin and adapted to depend through said loops, for the purpose set forth.

In testimony whereof I hereunto affix my signature, in the presence of two witnesses, this 6th day of July, 1904.

HUNTER H. DOVELL.
